UNITED STATES PATENT OFFICE

167,925

FLASHLIGHT CASING

Ewan Cameron, Jr., Clinton, Mass.

Application June 3, 1952, Serial No. 20,002

Term of patent 14 years

(Cl. D48—24)

To all whom it may concern:

Be it known that Ewan Cameron, Jr., a citizen of the Dominion of Canada, residing at Clinton, in the county of Worcester and State of Massachusetts, has invented a new, original, and ornamental Design for Flashlight Casing, of which the following is a specification, reference being had to the accompanying drawing, forming part thereof.

Fig. 1 is a front elevational view of a flashlight casing, showing my new design, and the rear being the same;

Fig. 2 is a side view thereof; and

Fig. 3 is a top end view thereof.

I claim:

The ornamental design for a flashlight casing, as shown and described.

EWAN CAMERON, JR.
